UNITED STATES PATENT OFFICE.

JOSEPH ENRIGHT, OF SAN JOSÉ, CALIFORNIA.

STEAM-BOILER FURNACE.

SPECIFICATION forming part of Letters Patent No. 241,480, dated May 17, 1881.

Application filed January 10, 1881. (Model.)

To all whom it may concern:

Be it known that I, JOSEPH ENRIGHT, of San José, Santa Clara county, State of California, have invented new and useful Improvements in Steam-Boiler Furnaces; and I do hereby declare the following description and accompanying drawings sufficient to enable any person skilled in the art or science to which they most nearly appertain to make and use my said invention without further invention or experiment.

My improvements consist in combining a water-chamber or water-bridge wall with water-grates within the furnace of a steam-boiler used for burning straw as fuel, and the peculiar manner of arranging the water-pipes which serve to connect the water-bridge wall with the boiler; also, in connecting a small steam-pipe with the dome of the boiler and placing it over the furnace-door, through which I convey a small jet of steam from the steam-boiler to the furnace, as will be hereinafter more fully shown and described.

In order to explain my improvements so that others will understand their nature and application, I refer to the accompanying drawings, forming part of this specification, in which—

Figure 1 is a longitudinal section of my boiler, showing the steam-pipe J. Fig. 2 is a front-end view, showing the connecting-pipes C C and the water-grates B B and the furnace-front E. Fig. 3 shows my improvements, consisting of water-bridge wall D, water-grates B B, connecting-pipes C C, and furnace-front E, removed from the steam-boiler furnace in a body. Fig. 4 is a side elevation of the rear or furnace-end of the boiler.

My improvements are especially applicable to steam-boiler furnaces of portable engines, known as "thrashing-engines," and using straw as fuel. When straw (which is a quick-burning fuel) is used in a steam-boiler furnace to generate steam, the feeding is continuous. Consequently a very high degree of heat is maintained, which ordinary bridge-walls and grates fail to stand for any length of time, which must be remedied in order to utilize straw as a fuel economically.

By my invention I am enabled to make a bridge-wall and grates which will withstand the severest test of heat. It is made hollow,

and has a constant circulation of water through it and through the pipes which form the grate into the boiler. The bridge-wall and furnace-front are connected together by the gratings, 55 and altogether form a removable grate or fire-pot, which fits snugly into its place in the steam-boiler furnace, and from which it may be removed at pleasure by disconnecting the pipes C from the pipes which connect their 60 outer ends with the boiler.

The bridge D is made so that it slides readily into the furnace-chamber A', which is surrounded by the water in the water-chamber A⁴ in the boiler A. It has its lateral edges curved to 65 correspond to and fit snugly against the sides of the furnace chamber. Its upper and under edges are straight and do not touch the sides of the furnace-chamber. A narrow throat is thus provided above it, for the smoke and heat 70 to pass from the grate to the ash-chamber A² in its rear, and an opening below it, through which the ashes may be drawn from the said chamber A². The water-back stands intermediate between the fire-front E and the ends of 75 the small flues A³, which pass through the water in the rear end of the boiler. When constructed and arranged as described it is specially adapted to that class of portable steam-boilers in which straw is employed as fuel. 80

I am also enabled by my peculiar construction of connecting-pipes to prevent the destruction of the joints by fire, they being connected on the outside with the steam-boiler. I am also enabled to remove with dispatch the 85 water-bridge wall and grate in a body from the furnace, for the purpose of cleaning and repairing.

In using straw as a fuel in portable steam thrashing-engines and boilers in the harvest-field to drive thrashing-machines, it is necessary to have a strong blast or draft in order to perfect combustion, and this is particularly essential when the straw used for fuel is wet or damp.

Heretofore the draft has been supplied by conveying the exhaust-steam from the engine through a pipe to the smoke-stack of the steam-boiler, and by closing or cramping the outlet, which causes a back-pressure on the engine, 100 thereby incurring a great loss of power.

I connect a small steam-pipe with the dome

of the boiler and insert it above the door of the straw-burning steam-boiler furnace, through which I convey a small jet of steam from the boiler to the furnace, thereby causing a strong draft or blast economically and sufficient to cause complete combustion of the straw, which causes the boiler to generate steam freely and sufficient to drive a thrashing-machine in the harvest-field to its fullest capacity without cramping the exhaust-pipe of the steam-engine, thereby saving both fuel and power.

Having thus described my invention, what I claim, and desire to secure by Letters Patent, is—

15 The combination, with the boiler A, constructed with a furnace-chamber, A', sur-

rounded by the water-chamber A⁴, of a removable water-back, D, sliding into and fitting snugly against the sides of the furnace-chamber, and having a draft-throat above it and an ash-opening below it, the circulating-pipes B B, connected to the water-back and to the removable furnace-front E, and the bent pipes C C, having one of their ends connected to the ends of the pipes B B on the outer side of the fire-front and their other ends carried to the outer side of and connected to the boiler A, substantially as set forth.
